his Attorney

UNITED STATES PATENT OFFICE.

OSMYN MOWERS, OF HOUSTON, TEXAS.

SWAB.

1,412,213.

Specification of Letters Patent. Patented Apr. 11, 1922.

Application filed April 18, 1921. Serial No. 462,385.

To all whom it may concern:

Be it known that I, OSMYN MOWERS, a citizen of the United States, residing at Houston, Harris County, Texas, have invented a certain new and useful Improvement in Swabs, of which the following is a full, clear, and exact description, such as will enable others skilled in the art to which it appertains to make and use the same.

10 My invention relates to an improvement in swabs for cleaning oil or water wells of liquid, especially where such liquid contains a quantity of sand, mud, or other abrasive material. Thus where a well has been 15 drilled and the casing set it is an ordinary practice to let a swab down into the fluid standing in the well and to get a load of the fluid and withdraw it from the well. This 20 operation is repeated until the well has been cleaned of fluid as far as possible.

An object of my invention is to provide a swab which may be introduced readily into the well and may be again readily withdrawn without danger of mutilation.

25 Another object is to provide a swab which will carry a heavy load without danger of breaking and which will operate for long periods of time without a great amount of wear. I desire to produce a swab of durable construction in which there will be 30 no likelihood of overload and which will operate rapidly in practice.

Referring to the drawing wherein like numerals of reference are applied to like parts in the two views, Fig. 1 is a central longitudinal section through a well casing showing my invention in elevation therein; and Fig. 2 is a broken longitudinal section showing details of construction of the cup or 40 "sucker" used in my improvement.

In the drawing I have illustrated in Fig. 1 my improvement in swabs as located within an outer casing 3. The swab is made up of a central supporting tube 4 of comparatively small diameter and may be a pipe from two to four inches in diameter. This pipe 4 is connected at its upper end by means of a swedged coupling 5 to a length of larger and heavier pipe 6, the pipe 6 having a bail 50 or some attaching means 7 at the upper end thereof to which may be secured the hoisting cable. The length of pipe 6 is included merely as a weight to force the swab downwardly into the well when it is being operated. At the lower end of the pipe 4 is a 55 valve seat 8 secured therein. Upon this

valve seat is a valve 9 such as is usually employed in bailing devices. It has a rounded upper end adequate to fit within the seat 8 and has a depending vane at the lower end 60 to assist in opening the valve to unload the contents of the pipe 4 when desired. Toward the upper end of the pipe 4 I contemplate perforating the pipe at 10 to allow a free outlet of fluid passing upwardly past 65 the valve.

The closure between the pipe 4 and the walls of the casing 3 is obtained in my device by the use of a plurality of cups or "suckers" 11. These suckers are spaced 70 slightly apart and cooperate when expanded in holding the oil or fluid above them from leaking backwardly into the well. Each of these suckers 11 comprises a downwardly tapered cup 12 made of leather, rubber or 75 some wear-resisting composition which is somewhat flexible. This cup is secured at its lower or smaller end to the pipe 4 by any well known means, but I have shown same as clamped securely to the pipe by 80 means of a coupling or collar 13 having an outwardly flared recess 14 in the upper end thereof to receive the lower end of the cup and force the same in fluid tight relation to the pipe 4. Cup 12 is reinforced and 85 supported by means of a plurality of inner resilient strips of metal 15. These reinforcing members are preferably made of straps of spring metal such as steel secured at the lower inner end of the cup by means of 90 rivets 16 and also at the upper end by a similar securing means 17. The supporting spring then extends upwardly above the cup and is secured at its upper end to a sliding collar 18. As will be apparent any suitable number of these supporting members 95 may be used but I have employed four in the embodiment shown in the drawing.

I also contemplate employing a second supporting strip of metal 19 similar in general construction to the members 15. These strips 19 are secured directly outside of the strips 15, being fastened at their upper ends to the sliding collar 18 by the same rivets or set screws 20, as are employed in 100 securing the supporting strips 15 thereto. The strips 19 are slightly longer than the inner strips 15, allowing free play of the same outside the cup 12 and are secured to the cup at the lower end thereof by means of 105 the rivets or screws 16 and also by means of the clamping collar 13.

The operation of my improved bailer will be similar to that of the ordinary bailer. It is secured to the lower end of the bailing line at 7, the weight of the device itself and the heavy length of pipe 6 above the same will force it downwardly through the fluid in the well. On its passage downwardly through the fluid the valve 9 will be raised from its seat and will allow the passage upwardly into the pipe 4 of the fluid. This fluid will pass upwardly and out the upper end of the pipe 6 or will find an outlet also through the perforations 10 in the pipe 4. Also the cups 12 will collapse a certain amount as shown in Fig. 2 so as to allow a considerable space between the same and the walls of the casing for the passage of the fluid.

When the device has been lowered down into the fluid for a sufficient distance to obtain a suitable load of fluid above the swab the bailing line and the swab thereon will be drawn upwardly. On this motion the valve 9 will drop into its seat preventing the passage downwardly of the fluid past this valve and the cups 11 will be expanded by the weight of fluid. They will be forced outwardly by the weight of fluid against the inner face of the casing. The supporting springs or straps of metal 15 and 19 will prevent the possibility of forcing the flexible cup downwardly too far, the ring 18 sliding downwardly along the pipe as the cup is expanded. It is obvious that without some supporting means such as the metal straps 15 and 19 the cup might be turned backwardly by the force of fluid above the same so as to turn the cup wrong side out and prevent the functioning of the swab. The outer straps 19 not only assist in supporting the cup properly, but also prevent the outer edge of the cup from mutilation when it is introduced into the well or withdrawn therefrom. Thus it will be seen that joints in the pipe upon which the edge of the cup 12 might otherwise catch and be torn will not engage the edge of the cup in such manner as to injure the same, it being protected from such action by the outer springs 19. A swab employing one only of these suckers would no doubt function to carry the moderate load but where a plurality of the same, such as is disclosed in the drawing, is employed a very heavy load of fluid may be carried without injury to the device. In fact, the load carried by this type of swab will be regulated mostly by the strength of the pipe and of the supporting cable.

This device may be quickly introduced into the well and again quickly withdrawn without danger of mutilation of the cups and when withdrawn the device may be lowered upon the derrick platform so as to

raise the foot valve 9 and the fluid inside the pipe 4 thus quickly discharged. 65

Having thus described my device, the objects and advantages of which will be apparent to one skilled in the art, without further description, what I claim as new and desire to protect by Letters Patent is: 70

1. In a swab, a central tubular member, an upwardly opening valve in the lower end thereof, a plurality of cups secured on the outer surface of said pipe, means to support said cups, and prevent the mutilation of the same and means to force said device downwardly into a well. 75

2. In a swab, a central supporting pipe, a weight thereon, cups on said pipe, said cups being made of flexible material, supporting means for each of said cups comprising strips of resilient material secured thereto and engaging a sliding ring on said pipe above said cup. 80

3. In a swab, a supporting pipe, cups mounted on said pipe, said cups comprising upwardly flaring members composed of flexible material, means to support said cups in erect position and means to protect the upper edges of said cups from mutilation in 90 the manner described. 85

4. In a swab, a supporting pipe, cups mounted thereon comprising upwardly flaring members of flexible material, means to secure their lower edges in fluid tight relation to said pipe, means to support said cups in operative position comprising strips of resilient metal secured on the inner face of each of said cups, and means to protect the upper edges from mutilation comprising a strip of resilient material between the edge of each of said cups and the wall of the well casing. 95 100

5. In a swab, a supporting pipe, a cup thereon of flexible material, resilient means to support said cup, means to protect the cup against mutilation, whereby said cup may collapse to allow a passage of fluid outside thereof when forced downwardly and may expand against the walls of the well casing 110 on movement upwardly. 105

6. In a swab, a supporting pipe, a flexible cup thereon, a plurality of supporting strips of resilient metal secured on the outer face thereof so as to protect the upper edge thereof and a supporting ring on said pipe to which ring said strips are secured. 115

7. A swab comprising a supporting pipe, a cup of flexible material secured thereto, means to support said cup resiliently, and means to protect said cup from excessive wear. 120

In testimony whereof, I hereunto affix my signature.

OSMYN MOWERS.
